UNITED STATES PATENT OFFICE.

OSCAR E. BURKHOLDER, OF SAN FRANCISCO, CALIFORNIA.

SECURING-PIN.

1,373,596.

Specification of Letters Patent.

Patented Apr. 5, 1921.

Application filed January 20, 1920. Serial No. 353,086.

To all whom it may concern:

Be it known that I, OSCAR E. BURKHOLDER, a citizen of the United States, residing in the city and county of San Francisco and State 5 of California, have invented a new and useful Improvement in Securing-Pins, of which the following is a full, clear, and exact description, such as will enable others skilled in the art to which it appertains to make and 10 use the same.

My invention relates to improvements in securing pins of the type used for hair pins, hat pins and other similar articles, wherein a pair of pins operate in conjunction with a 15 pair of tubular members, connected at one end, to inclose material fastened.

The primary object of the present invention is to provide an improved hair pin or hat pin.

20 A further object of the invention is to provide a pair of tubular members connected at one end to form a yoke and to move a pair of pins through the legs of said yoke to cross each other when projected beyond the free 25 ends of said yoke to inclose material being fastened therein.

I accomplish these and other objects by means of the device disclosed in the drawings forming a part of the present specification, 30 wherein like characters of reference are used to designate similar parts throughout the said specification and drawings, and in which—

Figure 1 is an enlarged elevation of my 35 improved securing pin;

Fig. 2 is a further enlarged broken, sectional view disclosing the means for preventing the withdrawal of the pins from the tubular member; and

40 Fig. 3 is also a further enlarged broken sectional view disclosing the manner in which the course or direction of the pins are changed when projected from the tubular members.

45 Referring to the drawings the numeral 1 is used to designate a pair of tubular members connected at one end as at 3 and provided with coaxial apertures 4 adjacent said connected ends.

50 The free ends of the members 1 are curved inwardly on their outer surfaces as at 6 and provided with a second set of apertures 7 on the inner surfaces of said ends which are pointed to facilitate passage through fabric, hair and the like.

55 A pair of pins 8 are slidably mounted

within the tubular members 1 and extend through the apertures 4 at the connected ends of said tubular members, said pins 8 being also connected as at 9 exteriorly of said 60 connected ends of the tubular members 1.

The pins 8 are provided with suitable projections 10 by means of a bent offset or any other suitable means to provide an obstruction adapted to prevent the passage of said 65 pins 8 through the apertures 4 of the members 1 whereby the entire withdrawal of said pins from the tubular members 8 may be prevented.

In operation the members 1, with the pins 70 8 receded, are passed through the material to be secured, as a lady's hat or hair, and after being placed inwardly as far as possible, such as placing a hair pin or the like, the pins 8 are projected through the apertures 7 adjacent the free ends of the members 1, the curved surfaces 6 operating to change the course of said pins 8 as they are projected and cause said pins to cross each other when projected fully beyond said free 80 ends, as disclosed in dotted lines in Fig. 1 of the drawings.

In this manner material between the tubular members 1 will be inclosed by said members and the crossed ends of the pins 8.

The pins 8 are sufficiently rigid to normally retain such material in position and thereby normally prevent withdrawal of the device.

To remove the device the pins 8, by means 90 of their connected ends as at 9, are receded into the tubular members 1 until the projections 10 thereon engage the connected ends of said tubular members thereby preventing further movement of the pins.

Having thus described my invention what I claim as new and desire to secure by Letters Patent is—

1. A securing pin comprising a pair of tubular members connected at one end and having the outer surfaces of the opposite ends curved inwardly and apertured; and a pair of pins slidably mounted within the tubular members and arranged to be moved by said curved ends to cross each other 105 when projected beyond said ends.

2. A securing pin comprising a pair of tubular members connected at one end and having the outer surfaces of the opposite ends curved inwardly and apertured, a pair 110 of pins slidably mounted within the tubular members and arranged to be moved by

said curved ends to cross each other when projected beyond said ends; and means for preventing withdrawal of the pins from the opposite ends of said tubular members.

5. 3. A securing pin comprising a pair of tubular members connected at one end and having their opposite ends pointed and curved inwardly on their surfaces and apertures on their inner surfaces adjacent said 10 curved ends; a pair of pins slidably mounted within the tubular members and arranged to be moved by the curved ends of said members to cross each other when projected beyond said curved ends.

15. 4. A securing pin comprising a pair of tubular members connected at one end and having their opposite ends pointed and curved inwardly on their outer surfaces and apertures on their inner surfaces adjacent 20 said curved ends; a pair of pins slidably mounted within the tubular members and connected exteriorly of the connected ends of said tubular members and arranged to be moved by the curved ends of said members to cross each other when projected beyond said curved ends; and means for preventing withdrawal of said pins from the connected ends of said tubular members.

5. A securing pin comprising a pair of 30 tubular members connected at one end and provided with curved outer surfaces at their opposite ends and apertures arranged on the inner surfaces and adjacent said ends, and likewise having a second set of apertures 35 registering coaxially with said tubular members adjacent their connected ends;

and a pair of pins slidably mounted within the tubular members and connected adjacent the connected ends of the tubular members exteriorly thereof and also arranged 40 to be moved to cross each other by the curved surfaces of the opposite ends of the tubular members when said pins are projected through the apertures adjacent thereto, said pins being likewise provided 45 with projections to prevent withdrawal of said pins from said tubular members.

6. A securing pin comprising a pair of tubular members connected at one end and provided with coaxial apertures on said 50 connected ends, the opposite ends of said tubular members being curved inwardly on the outer surfaces thereof and provided with apertures on their inner surfaces adjacent said ends; and pins slidably mounted within 55 the tubular members and projecting through the apertures at the connected end of said member and connected exteriorly thereof, said pins being moved to cross each other when projected through the apertures adjacent the curved ends and likewise provided with projections within the tubular members, said projections engaging the tubular members adjacent the apertures thereof adjacent the connected ends when 60 receded the tubular members to prevent entire withdrawal of said pins from said tubular members.

In witness whereof I hereunto set my signature.

OSCAR E. BURKHOLDER.
